CLAIM

We claim the ornamental design for a dispenser, as shown and described.

DESCRIPTION

FIG. 1 is a front, right, perspective view of the claimed design of a dispenser;

FIG. 2 is a front side view of the claimed design;

FIG. 3 is a rear side view of the claimed design;

FIG. 4 is a right side view of the claimed design;

FIG. 5 is a left side view of the claimed design;

FIG. 6 is a top view of the claimed design; and,

FIG. 7 is a bottom view of the claimed design.

The ornamental design which is claimed is shown in solid lines in the drawings. The evenly dashed broken lines illustrate portions of the dispenser that form no part of the claimed design. Broken lines formed of unequal length dashes (i.e., dash-dot) show boundaries between claimed and unclaimed portions of the design.
